COLLAR HOLDER HAVING ADJUSTABLE CLAMP MEMBERS

Leonard K. Berger, New York, N. Y.

Substituted for application Serial No. 536,443,
May 20, 1944. This application October 10,
1947, Serial No. 779,081

2 Claims. (Cl. 24—81)

1

This invention relates to new and useful improvements in a collar holder having adjustably mounted clamp members.

This is a substitute for my abandoned application, filed on May 20, 1944, Serial Number 536,443.

More specifically, the invention is characterized by the construction of an initialled collar holder characterized by having a tubular center piece and two initial carrying collar clamping members, at least one of which is removable from the tubular center piece.

A further object of this invention is to provide a collar holder as aforesaid in which both clamping members are removable from the center piece.

Still further it is proposed to provide a collar holder as aforesaid characterized by the clamping members being connectable with the center piece by a bayonet connection.

Still further, the invention has for an object the construction of collar clamping members in the center piece member and securing at least one clamping member therein by tits on one of the members fitting in sockets on the other of said members.

Still another object is to provide a collar holder as aforesaid adjustable in length.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

Fig. 1 is a perspective view of a collar holder constructed in accordance with this invention.

Fig. 2 is an elevation of one collar clamping member before it is associated with the rest of the holder.

Fig. 3 is an inverted plan view of the member shown in Fig. 2.

Fig. 4 is an inverted plan of the holder center piece and a collar clamping member permanently secured thereto.

Fig. 5 is an inverted perspective view of a collar holder center piece constructed in accordance with a modification of this invention.

Fig. 6 is an inverted perspective view of a portion of a collar clamping member adapted to be associated with the center piece shown in Fig. 5.

Fig. 6A is a perspective view of a collar holder embodying the center piece shown in Fig. 5 and two clamp members in accordance with that shown in Fig. 6.

Fig. 7 is a fragmentary perspective view, partly in section, of a collar holder center piece constructed in accordance with a further modification of this invention.

Fig. 8 is a perspective view of a portion of a

2

collar clamping means adapted to be associated with the center piece shown in Fig. 7.

Fig. 9 is a side elevation of a collar clamping member constructed in accordance with still another modification of this invention.

Fig. 10 is a perspective view of a collar holder center piece constructed in accordance with a further modification of this invention.

Fig. 11 is a perspective view of a portion of a collar clamping member adapted to be associated with the center piece of Fig. 10.

The collar holder according to the first form of the invention shown in Figs. 1 to 4, includes a hollow rectangular center piece 10 and two collar clamping members 11 and 12 connected to the center piece. Center piece 10 is formed of thin sheet metal bent into shape and having its seam 13 at the bottom. If desired it may be made of seamless tubular stock.

Members 11 and 12 are similar in construction. Each includes a top substantially straight bar 14. The bars 14 have initials 15 secured to the outer ends thereof by welding or soldering. Each bar 14 continues into a bottom curved bar 16 ending in a loop 17 disposed adjacent but in slightly spaced relation from the bar 14 beneath the initial 15 secured thereto. One of the members 11 or 12 may be permanently secured in the center piece 10 or both may be removably secured therein.

The hollow interior of the center pin 10 is substantially rectangular in cross section. Bars 14 and 16 are secured together at their ends disposed in the center piece, as by welding or soldering. The secured ends of the bars 14 and 16 form a portion 18 rectangular in cross section and of a size to frictionally fit into the center piece 10. The complete holder, as shown in Fig. 1, is adapted to bridge two parts of a shirt collar behind the knot of a necktie in a well known manner.

The collar holder is, as aforescribed, formed of at least two separate parts. For instance, one part may be the member 11 and the other part may be the center piece 10 and the member 12 permanently secured thereto. The reason for so constructing the holder is so that combinations of initials may be easily secured without delay by a clerk of a store selling the holder to a customer. That is to say, if a person whose initials are N—B wishes to buy the collar holder of the present invention with his initials thereon, the clerk, who has a large number of members similar to member 11 with initials thereon from A-Z, need only choose one with the initial N and similarly choose a center piece 10 with a member 12 having permanently secured thereto the initial B and put them together by disposing the portion 18 of member 11 in the center piece to be thereby able to immediately supply his customer with the collar holder with the initials on it without delay.

While it is contemplated that the portion 18 will fit with a squeeze fit in the center piece so that it will be secured therein, if desired the center piece may be squeezed with a pair of pliers to firmly grip the portion 18, the slot 13 permitting this without deforming the center piece. If both members 11 and 12 are separate from the center piece 10, each may be assembled therewith in the aforescribed manner.

In the modification of the invention shown in Figs. 5, 6 and 6A, the construction of the collar holder is similar to that previously described except that the end portions 18' of the clamp members 11' and 12' are rounded and each has a bayonet joint pin 19 secured in the bottom face thereof. The center piece 10' is cylindrical and is provided with two series of bayonet joint sockets 20 opening into the open seam 13'. This provides means for positively securing the collar clamping members 11' and 12' to the center piece 10', and also means for selectively adjusting the length of the collar holder. If desired, the sockets 20 need only be supplied on one side of the center piece, the collar clamping member at the other side being permanently secured to the center piece. In other respects, the collar holder of Figs. 5 and 6 is similar to the collar holder of Figs. 1-4.

In the modification of the invention shown in Figs. 7-8, the construction of the collar holder is similar to the collar holder of Figs. 1-4 except that the center piece 10'' is provided with an initial 15' representing the middle initial of a person's name and therefore it is contemplated that both collar clamping members will be removably associated with the center piece 10''. However, if the initial 15' is omitted, then one clamping member can be permanently secured to the center piece. Furthermore the side walls of the center piece 10'' are provided with two series of recesses 21 adapted to coact with tits 22 formed on the collar clamping member 11'' (Fig. 8) for adjustably positively securing the collar clamping member in the center piece.

In Fig. 9 a collar clamping member 11''' is shown formed of one piece of metal bent into shape. In other respects it is similar to the collar clamping member 11.

In the modification of the invention shown in Figs. 10 and 11, the construction of the collar holder is similar to the collar holder of Figs. 1-4 except that the center piece 10''' is seamless and has two tits 23 formed in its upper and lower faces for coaction with serrated grooves 24 formed in the upper and lower faces of the member 11''' whereby member 11''' may be adjustably secured in the center piece. The other collar clamping member will similarly be secured in the center piece.

It is to be understood that the initials 15, 15', etc., may also be interchangeably placed on their corresponding bars 14.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent is:

1. In a collar holder having a tubular center piece and separate collar clamping members, said clamping members having end portions slidably and turnably extended into the ends of the center piece, means for adjustably removably attaching the collar clamping members to the tubular center piece, the tubular center piece being formed in one face along its length with a seam which opens to the ends of the tubular piece, the tubular center piece being formed adjacent its ends with spaced sets of spaced slots in the material thereof to one side of said seam, and a pin projecting from one end of each of the collar clamping members, said slots being in communication with said seam, whereby the ends of the clamping members carrying said pins may be slid into the ends of the center piece with said pins sliding in said seam until said pins reach a position aligned with a desired slot of each set of said slots after which the clamping members can be given a slight turn relative to the center piece in a direction to cause the pins to enter the slots with which they were aligned securing the clamping members to the center piece.

2. In a collar holder having a tubular center piece and separate collar clamping members, said clamping members having end portions slidably and turnably extended into the ends of the center piece, means for adjustably removably attaching the collar clamping members to the tubular center piece, the tubular center piece being formed in one face along its length with a seam which opens to the ends of the tubular piece, the tubular center piece being formed adjacent its ends with spaced sets of spaced slots in the material thereof to one side of said seam, and a pin projecting from one end of each of the collar clamping members, said slots being in communication with said seam, whereby the ends of the clamping members carrying said pins may be slid into the ends of the center piece with said pins sliding in said seam until said pins reach a position aligned with a desired slot of each set of said slots after which the clamping members can be given a slight turn relative to the center piece in a direction to cause the pins to enter the slots with which they were aligned securing the clamping members to the center piece, each of said slots being a bayonet slot having an offset end extended parallel to said seam, said offset ends of the bayonet slots of each set of slots being directed toward the adjacent end of the center piece, whereby the clamping members may be slid longitudinally outward relative to the center piece to cause the pins to enter the offset ends of the bayonet slots after the clamping members have been turned relative to the center piece.
